UNITED STATES PATENT OFFICE

ARCHIBALD G. SHAVER, OF CHICAGO, ILLINOIS, ASSIGNOR TO THE REGAN SAFETY DEVICES COMPANY, INC., OF NEW YORK, N. Y., A CORPORATION OF NEW YORK

ALTERNATING-CURRENT INTERMITTENT-INDUCTION-TYPE TRAIN CONTROL

Application filed October 10, 1921. Serial No. 506,595.

This invention relates to a train control system, and more particularly to a train control system of the induction type, and has special reference to the provision of an induction system arranged to be connected to and influenced by a block signalling system, with the induction system responsive to "safety", "caution" and "danger" track conditions to produce corresponding "clear", "caution" and "stop" effects on the train.

A principal object of the present invention comprehends the provision of an induction train control system in which train carried mechanism is operated to produce a plurality of effects such as proceed, speed restrictive and stop effects responsive to the cooperation between train and track magnetic elements or inductoriums with the train carried mechanism given a deenergizing or tripping operation in each section or block so as to condition the same for further operation and so as to determine the operability thereof to keep the same in proper working order at all times.

A further principal object of the invention relates to the provision of an induction train control system of the type referred to in which the train and track magnetic elements or inductoriums are operated by train carried energy.

Further objects of the invention relate to the provision of an induction train control system in which the train carried mechanism includes a pneumatic valve electrically controlled over a normally closed vehicle circuit, and employing a combined reservoir and brake valve of the type shown in my co-pending Patent No. 1,411,526 of April 4, 1922, in addition to a speed circuit controller similar to that shown and described in my co-pending application filed June 10, 1919, Serial No. 303,191, whereby the pneumatic valve, normally maintained energized when the train is moving from one point to another, continues to be energized under "clear" and "caution" conditions, but is deenergized under "danger" conditions, the said pneumatic valve being placed under the control of the speed circuit controller under "caution" conditions.

Still further objects of the invention are the provision of an inductive train control system of the nature referred to in which an alternating current or like source of energy is employed, the present invention being particularly an improvement on the induction train control system disclosed and claimed in my copending application Serial No. 422,598 of November 8, 1920; and the provision of an intermittent induction type of train control system in which an alternating current generator or like source of energy is carried upon the train and is connected to influence inductively coupled coils in the nature of a transformer, the magnetic flux to the secondary coil of which is shunted by movement of the coils over a roadside magnetic element to produce or initiate in each track section or block an initiating, deenergizing or tripping operation of train control mechanism, cooperating inductoriums responsive to track conditions being provided for determining the further state of operation of the train controlled mechanism after such initiating operation and for resetting or restoring the same under a "proceed" track condition.

To the accomplishment of the foregoing and such other objects as may hereinafter appear, my invention consists in the elements and their relation one to the other, as hereinafter particularly described and sought to be defined in the claims, reference being had to the accompanying drawing which shows a preferred embodiment of my invention, and in which:—

Figure 1 is a diagrammatic view of the complete apparatus for producing clear, caution and stop effects on the train, as carried by the locomotive or vehicle, while a portion of the roadside apparatus is illustrated.

Figure 2 is a view of a modified system for producing clear and stop or limited speed control effects.

Figure 3 is a side elevation of a transformer in conjunction with an adjacent portion of the rail.

Figure 4 is an end elevation thereof, showing the two rails.

Figure 5 is a plan view of the same.

Figure 6 is a view looking from the end thereof, showing the relative arrangement of the inductoriums and the receiving and transmitting coils thereof.

Figure 7 is a plan view showing the general scheme as applied to curve protection.

Figure 8 is a detail view of the resetting transformer used as above.

Figure 9 is a diagrammatic view showing the present inductive arrangement as applied to road-crossing bells or signals.

Referring now more in detail to the drawings, and more particularly to Figs. 1 and 3 to 6 thereof, there is provided, as disclosed in my copending application Serial No. 422,598, a train control mechanism which comprises the electromagnet M active for controlling the operation of the combined reservoir and brake valve N, the detail construction of which is set forth in my Patent No. 1,411,526 of April 4, 1922. The electromagnet M is controlled by a two-element relay B—B'; when the currents in the elements B—B' are in phase as under "clear" track conditions, the contacts 67, 68 and 69 controlled by the relay are caused to assume the full-line position shown in Fig. 1, and when the currents are out of phase, as for example 180° out of phase, as under "caution" track conditions, the said contacts are caused to assume another position as the inclined dotted-line position, and when either of the relay elements B—B' is deenergized, as under "danger" track conditions, the contacts are caused to open and assume a neutral vertical dotted-line position shown in Fig. 1.

With this operation of the relay B—B', under "clear" roadside conditions the electromagnet M is energized to produce a train "proceed" effect in the valve N, the electromagnet M being normally energized from a train carried alternating current source of energy G by the following circuit: generator G, conductors 2, 3, 4, 30 and 32, contact 69 in full line position, conductor 29, electromagnet M, and conductors 28, 27 and 78 to the generator G.

Under "caution" roadside conditions the train controlling mechanism M—N is placed in circuit with a speed circuit controller S so as to produce a vehicle speed restrictive effect, the electromagnet M being energized when the train is proceeding at or below, and being deenergized when the train is proceeding above a predetermined or permissive speed, the said circuit including the generator G, conductors 2, 3, 4 and 30, contact 77 of the speed circuit controller closed when the train is running at or below a predetermined speed and opened when the train exceeds such predetermined speed, conductor 31, contact 69 in the inclined dotted line position, conductor 29, magnet M, conductors 28, 27 and 78, to generator G.

Under "danger" track conditions with the

contact 69 in a neutral vertical position, the circuit to the electromagnet M is opened, the electromagnet deenergized and the valve N operated to set the brakes of the train and to disconnect the engineer's brake valve from the main reservoir as disclosed in my Patent No. 1,411,526 above mentioned.

For normally maintaining the relay contact 69 in either of its full or dotted line positions to maintain unlimited speed or restrictive speed effects on the train, I provide a stick circuit including one element of the relay B—B' and controlled by another two-element relay A—A'. For normal or unlimited speed conditions the stick circuit comprises the generator G, conductors 78, 332 and 331, armature contact 65 controlled by the element A' of the relay, conductor 431, resistance R, conductor 16, armature 67 in full line position, conductors 10, 14 and 79, element B', conductors 55, 13, 12 and 11, armature contact 68 in full line position, conductor 15, resistance R', conductor 432, armature 66 controlled by relay element A', and conductors 333 and 1 back to generator G. The element B of the relay B—B' is energized through the circuit including the generator G, the conductors 7, 47, 48 and 2. Under these normal conditions the currents in the elements B—B' are in phase, and the contacts 67, 68 and 69 are actuated by the relay to assume and maintain the full line position.

When the currents in the elements B—B' are out of phase, as for example 180 degrees, out of phase, this being a condition produced by means to be described hereinafter, the contacts 67, 68 and 69 are moved to the right-hand dotted line position and are retained in this position by the train stick circuit as follows: from generator G, conductors 78, 332, 331, contact 65, conductor 431, resistance R, conductor 16, contact 67 in dotted line position, conductors 20, 13 and 55, element B', conductors 79, 14, 17 and 18, contact 68 in dotted line position, conductor 15, resistance R', conductor 432, contact 66 and conductors 333 and 1. With this circuit it will be noted that the current in the elements B—B' are out of phase and the stick circuit will therefore maintain the contacts 67 to 69 in their dotted line positions.

Under "danger" track conditions the stick circuit is broken by the opening of the contacts 65 and 66 controlled by the relay A—A' as to be described presently, and the contacts 67 to 69 assume the vertical dotted line positions, with the result that the electromagnet M is deenergized.

For controlling the positioning of the contacts of the relay B—B' so as to impress upon the train controlling means M—N a desired effect, I provide cooperating vehicle and roadside magnetic means or elements, and more specifically vehicle and roadside inductoriums, the roadside inductoriums being preferably

under the control of a block signalling system or similar means and being influenced by the same to respond to "safe", "caution" and "danger" track conditions, and to indicate such conditions, and the vehicle inductoriums being arranged for movement over the roadside inductoriums and to cooperate with the latter to receive and transmit the indications of the same to the train circuits and to the relay B—B' to correspondingly influence and operate the same. To these ends I provide a train transmitting inductorium 63 having the coil 60 connected to the vehicle source of energy G by means of the conductors 2 to 7 inclusive, and a train receiving inductorium 64 having a coil 62 connected to operate and control a normally deenergized two-element relay C—C', the element C' being connected to the inductorium coil 62 by means of the conductors 41, 42 and 76, a condenser L being employed in this circuit to correct the phase of the current therein, that is, to return the current to its actual phase relation relative to the various transformers herein set forth should the same be caused to lag, the said condenser operating so that the phase will correspond with that delivered directly from the generator terminals, the element C of the relay being connected to the generator G by means of the conductors 2, 50, 49 and 7. For cooperation with the train transmitting and receiving inductoriums, I provide roadside receiving and transmitting inductoriums 63' and 64', the said inductoriums being provided with the coils 60' and 62' electrically connected by means operative to reverse and to break the circuit connections between the said inductoriums, the said means comprising the make and break contacts 72 and 73 under the control of a home relay H and the pole changing contacts 74 and 75 under the control of a distant relay D', energization of the home and distant relays H and D' taking place under "safety" track conditions resulting in the positioning of the contacts as shown in Fig. 1 to connect the coils 60' and 62' by means of the circuit including the conductor 39, the contact 72, conductor 38, contact 74, conductor 36, coil 62', conductor 35, contact 75, conductor 34, contact 73, conductor 33, and coil 60'. When under "caution" track conditions the relay D' is deenergized, the contacts 74 and 75 are released to reverse the circuit connections between the coils 60' and 62'. When under "danger" track conditions the home relay H is deenergized, the contacts 72 and 73 are actuated to break the connections between the coils 60' and 62'.

With this construction, it will be seen that in the movement of the train and in the passage of the train inductoriums over the track inductoriums, an impulse will be transmitted from the train transmitting inductorium 63 to the track receiving inductorium 63', and that such impulse may be transmitted in a given phase, modified to a reverse or opposite phase or inhibited for influencing the track inductorium 64' for in turn influencing the train receiving inductorium 64 to energize the element C' of the relay with current in a given phase or in an opposite phase under "safe" and "caution" conditions respectively, the transmission, modification or inhibiting of the impulse received by the inductorium 60' being controlled by the circuit make and break and pole changing devices which in turn are influenced by the home and distant relays H and D' of the block signalling system. It will be noted that the cooperation between the train and track inductoriums is momentary as the former moves over the latter in the movement of the vehicle, a set of track inductoriums being provided for each section or block of the track.

Controlled by the relay C—C' there are provided contact armatures 70 and 71 which under normal conditions assume the vertical dotted line positions shown in the figure due to the normal deenergization of the element C', the said contacts being moved to the full-line position shown when the element C' is energized with current in phase with the energizing current in the element C, and being moved to assume the inclined dotted line position shown in the figure when the element C' is energized with current of an opposite phase.

When under "safe" track conditions, the contacts 70 and 71 are made to momentarily assume full line position, the element B' of the relay B—B' is energized by the closing of the following circuit: generator G, conductors 2, 3 and 9, armature 71 in full line position, conductors 19, 12, 13 and 55, element B', conductors 79, 14, 17, 21 and 25, contact 70 in full line position, and conductors 22 and 7, the energization of the element B' by this circuit causing the armatures 67 to 69 thereof to assume the full line position to close the stick circuit and the circuit of the electromagnet M, producing "clear" or "proceed" conditions on the train.

When under "caution" track conditions the contacts 70 and 71 are momentarily caused to assume the inclined dotted line position, the element B' is energized by current having a phase opposite to that of the current in the element B by means of the following circuit: generator G, conductors 2, 3, 9, contact 71 dotted line position, conductors 24, 21, 17, 14, 79, element B', conductors 55, 13, 12, 19 and 23, contact 70 in dotted line position, and conductors 22 and 7. With the closing of this circuit the element B' is energized by current opposite in phase to that in the element B, and the contacts 67 to 69 are moved to the inclined dotted line position to close the stick circuit and the circuit including the electromagnet M and the speed controller S, produc-

- ing "caution" or speed restrictive conditions on the train.
- When under "danger" track conditions the element C' is not energized, the controlling or operating circuit of the element B' is not closed, and should the contacts 67 to 69 be in the vertical dotted line position, the said contacts will remain in such position for producing a "stop" effect on the train.
- For the purpose of conditioning the vehicle carried mechanism for operation and control by the train and track inductoriums so that the train circuits are made to respond to the indications of the track inductoriums, and for the further purpose of automatically giving the train control apparatus a test operation in each section or block in order to automatically check the operability of the same at all times, there is provided cooperating train and track magnetic means for periodically deenergizing the element B' of the relay B—B', and more specifically for opening the stick circuit thereof at the contacts 65 and 66. To this end the relay A—A' heretofore mentioned is provided, the element A thereof being always energized from the generator G and connected thereto by means of the conductors 1, 333, 351, 341, 332 and 78, the element A' being connected to be energized by a coil D by means of the conductors 45 and 46, the said coil D being inductively coupled to another coil J which in turn is connected to be energized by the generator G by means of the conductors 1, 26, 27 and 78. The inductively coupled coils D and J comprise or constitute a transformer provided with a core having magnetic reluctance between the coils, the said magnetic reluctance being preferably provided by an air gap V between the pole pieces E and F of the transformer cores, the coils J and D constituting the primary and secondary coils respectively of said transformer. Cooperating with the transformer D—J there is provided for each section or block an inert track element I which is intended for cooperation with extended pole pieces F' forming part of the core piece of the primary coil J, the pole pieces F' being adapted to cover the track element I in the passage of the vehicle thereover. With this construction it will be seen that normally when the train is running between track elements, the magnetic flux transmitted through the pole pieces F and E induces a current in the coil D sufficient to energize the element A' of the relay to normally keep the armatures 65 and 66 closed. When the transformer D—J covers the track element I, the magnetic flux passes from the core piece of the coil J down to one leg F' thereof to the track element I and through said element to another leg F' of the core piece as clearly shown for example in Fig. 4 of the drawings, the passing of the flux through the inert track element I resulting in a diverting or shunting of the magnetic flux from the core piece E—E of the coil D, the coil D being magnetically shunted, causing a substantial deenergization of the relay element A', with the result that the armature contacts 65 and 66 are opened, opening the stick circuit to the element B'. This shunting action is momentary only, and after the transformer D—J passes the inert track element I, the magnetic flux through the core of the coil D is re-established, energizing the relay element A' for closing the contacts 65 and 66. With this construction it will therefore be seen that in each section or block of the track the stick circuit of the relay element B' is opened and the contacts controlled thereby moved to vertical open position, conditioning the relay for response to the operation of the train and track inductoriums heretofore described, the train and track inductoriums being brought into cooperative relation immediately after the shunting operation of the coil D takes place, as will clearly appear from a consideration of Fig. 1 of the drawings, the time interval between the shunting action and the operation of the inductoriums being insufficient to permit the brakes of the train to be set.
- Experiments seem to indicate that the theory of operation or action of the transformer combination D—J and of the inductive influence of the inert inductor I to produce the magnetic shunting of the secondary of the transformer or shunting or diverting of the lines of flux may be taken substantially as follows, it being understood, however, that this theory of operation is given by way of explanation only, and not by way of limitation of the invention:
- If we let M =total M. M. F., the magneto motive force in the magnetic circuit of the transformer D—J.
- Let ϕ =total flux.
- R_j =reluctance of the primary J.
- R_r =reluctance of the remainder of the magnetic circuit.
- Then
- $$M = \phi(R_j + R_r) \quad (1)$$
- Transposing,
- $$M - \phi R_j = \phi R_r \quad (2)$$
- Equation (1) shows that the total magnetomotive force is made up of the magnetomotive force active on the primary and the magnetomotive force active on the remainder of the magnetic circuit. In Equation (2) the quantity ϕR_r may be considered the magnetic potential difference which is effective on the remainder of the magnetic circuit for energizing purposes and more particularly for energizing the secondary D.
- When the vehicle carried transformer D—J moves over the track element I, two effects are produced, substantially as follows:
- (a) when the vehicle carried transformer

inductor moves over the track element the flux ϕ increases and since R_j is constant, the product ϕR_j increases, and from Equation (2) it will be seen (assuming M to remain constant) that the effective magnetic potential difference ϕR_r operative for energizing purposes decreases so that the energizing current for the relay $A-A'$ is effectively decreased.

(b) The magnetomotive force M , however, does not remain constant. When the vehicle carried transformer moves over the track element, the reactive effect on the vehicle carried inductor due to the decrease in reluctance in the magnetic circuit produces a decrease in the magnetomotive force M since the inductance of the energizing primary coil is increased with a corresponding decrease in energizing current. The magnetomotive force (ampere turns) therefore is decreased and thus the difference between this and ϕR_j is decreased still further, the resulting magnetic potential difference active for energizing the secondary being thereby still further reduced. Experiments appear to determine that the decrease in the magnetic potential difference due to the first effect (a) is the more predominant of the two, the resultant change being due substantially to this factor, the magnetic flux through the secondary being therefore actually shunted or diverted, although part of the total magnetic flux is somewhat decreased due to the second mentioned factor (b).

The operation of the system thus far described will in the main be apparent from the above detailed description thereof. It will be seen that in each section or block the inert magnetic shunting member I of the track mechanism will momentarily magnetically shunt the coil D , causing an opening or tripping of the stick circuit to the relay element B' , releasing the armature contacts 67 to 69 thereof. Immediately after this shunting or tripping action the train and track inductoriums 63, 64 and 63' and 64', are brought into cooperation to determine the further state of operation of the relay element B' . Under "safe" track conditions an impulse is transmitted to the train inductorium 64 to momentarily operate the reset relay element C' to actuate the contacts 70 and 71 to normal full line position, this in turn closing a circuit to the relay element B' to energize the same with "in phase" current, such energization resulting in the contacts 67 to 69 assuming their full line position for closing the stick circuit and the circuit of the electromagnet M , the said stick circuit being thereafter maintained closed by the re-energization of the relay element A' after the passage of the transformer $D-J$ beyond the track element I . Under "caution" track conditions an impulse of opposite phase will be transmitted to the train inductorium 64 for mo-

mentarily energizing the element C' with "out of phase" current, this momentarily closing an energizing circuit to the relay element B' with an "out of phase" current energizing the same for moving the contacts 67 to 69 to their dotted line positions, placing the train under speed restrictive operation. Under "danger" track conditions no impulse is transmitted to the train inductorium, with the result that the relay element C' remains deenergized and the relay element B' is unenergized and the contacts controlled thereby remain in neutral circuit opening position for bringing the train to a halt.

After the train has been brought to a halt, the same may be again set in motion by the operation of a release key K operated by the engineer so as to cause the members 80 and 81 to connect the relay element B' to the generator G by means of the circuit including the generator, conductors 2 and 54, member 81, conductors 53 and 79, relay element B' , conductors 55 and 51, member 80, and conductor 52 to the generator G , this connection causing the energization of element B' with an out of phase current so that the armature contacts 67 and 68 will be moved to the inclined dotted position, thus placing the speed circuit controller in circuit with the electromagnet M so that the train can proceed under or at a predetermined speed only.

The resistances R and R' which are placed in the train stick circuit in line with the conductors 16 and 15 respectively are provided in order to prevent a momentary short-circuiting of the generator G which would take place should the vehicle be standing in a position with the train inductoriums in inductive relation to the track inductoriums, with the track condition suddenly changed from "clear" to "caution".

In the diagram as shown in Fig. 2 the same system is shown in a simplified form, the system being used only for producing the "stop" or speed limiting effect. In this instance a generator G^2 is employed, and is connected to control the coil J' of a transformer D^2-J' by means of the conductors 1^a, 3^a, 7^a and 2^a, the coil J' being provided with the core pieces or legs F^2 and F^3 , which correspond to the same elements as shown in Fig. 1. The relay A^2 is supplied with alternating current through the transformer D^2-J' , transformer action taking place between the core pieces E^2 and F^2 and through the air gap V' . This relay is normally held energized through the following circuits which include the primary circuit comprising the generator G^2 , conductors 2^a, 7^a, coil J' , conductors 3^a and 1^a, this causing current to be induced in the coil D^2 of the secondary circuit comprising the said coil, conductors 9^a and 10^a, armature contact 26^a, conductors 13^a and 12^a, coil A^2 and conductor 8^a. The armature 26^a is a stick armature, the relay 130

A² being in a stick circuit controlled by the transformer D²-J' which in turn is controlled to operate as follows: The legs or branches F³ of the core of the primary coil J' of the transformer are so proportioned that when the transformer moves over the inert magnetic element I² the magnetic field of the coil J' is completed through the element I² and the magnetic lines of flux are shunted from the core of secondary coil D² of the transformer, the element I² thus acting as a shunt for the magnetic field energizing the secondary coil, causing the deenergization of the relay A² and the opening 10 of the contact 26^a, said coil A² remaining deenergized until restored as hereinafter explained. The operation of the vehicle carried inductively coupled coils and the road-side inductor when a tripping effect is produced is therefore to effect a change in the 15 energy or flux transference between the primary and secondary coils of the inductively coupled coils such as to effectively deenergize the relay A² for tripping the train or 20 vehicle carried mechanism.

For operating or controlling the operation of the relay A², there are provided the train and track inductoriums including the coil 60^a which is connected to be energized from the 25 generator G² by means of the circuit including the generator, conductors 1^a and 19^b, coil 60^a and conductors 19^a and 2^a. The coil 60^a is adapted to cooperate with the track inductorium coil 60^b for energizing the latter, the 30 impulse generated in the coil 60^b being transmitted under normal conditions to the track coil 62^b adapted to cooperate with the vehicle inductorium coil 62^a. Both of the coils 60^b and 62^b which preferable, although not necessarily, have an iron core, are included 35 in the following circuit: the coil 60^b, conductor 23^a, circuit controlling switch 30^a, conductor 20^a, coil 62^b, conductor 21^a, circuit controlling switch 29^a, and the conductor 22^a. The train inductorium coil 62^a controls a 40 relay C² by a circuit including the conductor 17^a, coil 62^a, and the conductor 16^a. The relay C² controls the armature 28^a, which is included in the following circuit: conductors 45 35^a, 15^a, and 9^a, coil D², conductors 8^a, relay A², conductors 12^a, 14^a, and 36^a, and the contact 28^a. Normally this circuit is open. When, however, the coils 60^a and 62^a are positioned over the track coils 60^b and 62^b, provided that the switches 29^a and 30^a are closed, 50 then current is induced through the coil 60^a in the coil 60^b, energizing the circuit connecting it with the coil 62^b, and also energizing the same, which in turn energizes the coil 62^a and which establishes a current to energize the relay C². Contact 28^a is therefore attracted, energizing coil A², in turn attracting the armature contact 26^a so that the coil of the relay A² is again energized through 55 the coil D², which latter has become energized again as soon as the pole pieces F² and F³ are without the influence of the track element I².

The magnet M² is included in the following circuit, namely, generator G², conductors 1^a, 3^a, and 5^a, contact 27^a, closed on its front contact, conductors 4^a, M², 6^a, 7^a and 2^a. It will be noted that as soon as the contact 27^a is open, magnet M² is de-energized, so that the brakes are applied and the train brought to a stop through the combined reservoir and brake valve N². In order to reestablish the circuit, the release key K² must be operated, which causes the energization of the relay A² through the conductors 31^a, 15^a and 9^a, and the coil D² which is energized, conductors 8^a, relay A², and conductors 12^a, 14^a and 32^a. This action causes the energization of the magnet N² and consequently restores the valve M² to normal position.

In order that the present apparatus may be used for curve protection the circuits as illustrated in Figs. 7 and 8, which are slight modifications of those shown in Figs. 1 and 2, are employed. In these circuits the inductorium or inert magnetic element J⁴ is located exteriorly of the track at the beginning of the curve, while inductoriums 63^b and 64^b are located at the end of the curve, thus providing a means that will cause the transformer A³ to be operated by the inductorium J⁴ for reducing the speed of the train while making the curve, train inductoriums 63^c and 64^c being operated by the track inductoriums 63^b and 64^b for restoring the vehicle apparatus to permit it to proceed under normal conditions after rounding the curve. The vehicle circuit arrangement consists primarily of the generator G³ which controls the coil D³ of the transformer A³ similar to that heretofore described, which controls the energization of the train inductorium 64^c. The inductorium 63^c is connected to operate the relay R³, the latter controlling the stick armature r³, while the transformer A³ is connected to operate the relay R' for controlling the stick armature r. The relay R² is provided with the armature contacts r' and r'' for controlling the connection of the electromagnet M³ and the speed circuit controller S³ across the terminals of the generator G³, the magnet being connected across the generator terminals when the armatures r' and r'' are in their upper or full line position and the electromagnet M³ being connected in series with the speed circuit controller S³ across the generator terminals when the armatures r' and r'' are moved to release, dotted line, positions shown in the figure. With this construction it will be seen that as the transformer A³ passes the inert element J⁴, the relay R' will be deenergized and the stick armature r will be released to in turn deenergize the relay R², both of whose stick armatures r' and r'' will assume dotted line position and thus con-

nect the speed controller in circuit with the electromagnet M^3 . The speed controller S^3 being set for a predetermined speed will open the circuit to the magnet M^3 if the train exceeds the predetermined speed, and the brakes 5 of the train will be applied for reducing the speed thereof. Should the train be moving below the predetermined speed, the circuit including the generator and magnet M^3 will 10 remain closed so that the train will proceed around the curve without automatic control until the inductoriums 63^c and 64^c cooperate inductively with the respective track inductoriums 63^b and 64^b , at which time the relay R^3 will be momentarily energized, attracting 15 the armature r^3 , placing the relay R^2 in circuit with the armatures r and r^3 , the relay R^2 being thereby energized to attract its armature contacts to full position and hold the 20 same in such position.

Fig. 9 shows the bell B^4 in circuit with the battery B^5 which is controlled by the relay C^4 which is connected in circuit with the track transformer 63^e so that every time 25 the vehicle transformer 60^e passes thereover the bell circuit will be closed, thus ringing the bell at a road crossing.

While there has been illustrated an arrangement of circuits and a possible location 30 of the apparatus upon the trackway, I do not wish to be confined to this particular arrangement, as it is well understood that there are other arrangements of circuits that may be used that will yield the same results 35 as herein indicated and set forth.

Although the apparatus is illustrated only as applied to trackway and trains, it is apparent that it can be used with any form of apparatus where a moving element is to be 40 controlled along a predetermined pathway such as cableways, store delivery mechanism or the like.

While I have shown my device in the preferred form, it will be apparent that many 45 changes and modifications may be made in the structure disclosed, without departing from the spirit of the invention, defined in the following claims.

What I claim as new is:

50 1. In an alternating current inductive train control system, vehicle carried train control mechanism, means for periodically influencing the same in the movement of the vehicle on a roadway, means for periodically determining the further state of operation 55 of the same when so influenced comprising vehicle impulse transmitting and receiving inductoriums, an alternating current source of energy therefor, and track impulse receiving and transmitting inductoriums cooperating therewith.

2. In an alternating current inductive train 65 control system, vehicle carried train control mechanism, inductive means for periodically influencing the same in the movement of

the vehicle on a roadway, means for periodically determining the further state of operation of the same when so influenced comprising vehicle impulse transmitting and receiving inductoriums, an alternating current source of energy therefor, and track impulse receiving and transmitting inductoriums cooperating therewith. 70

3. In an alternating current trains control system, vehicle carried mechanism, means including roadside mechanism for influencing the same in the movement of the vehicle over a roadway, and means for determining the operation of the same when so influenced including cooperating vehicle and roadside magnetic elements, and a vehicle alternating current source of energy for energizing the vehicle magnetic element by way of the roadside magnetic element. 75

4. In an alternating current train control system, vehicle carried mechanism, means comprising roadside mechanism for influencing the same in the movement of the vehicle to produce a controlling effect therein, and means for determining the state of operation thereof, when the same is controlled including cooperative vehicle and roadside inductive elements and a vehicle alternating current source of energy for operating the said inductive elements. 80

5. In an alternating current induction train control system, vehicle carried mechanism including a normally closed operating circuit, means comprising roadside mechanism for opening the circuit in the movement of the vehicle, and means for determining the further state of operation thereof including cooperating vehicle and roadside inductive elements and a vehicle alternating current source of energy for operating the 100 inductive elements. 105

6. In an alternating current induction train control system, vehicle carried mechanism including a normally closed operating circuit, a vehicle alternating current source 110 of energy therefor, means comprising roadside mechanism for opening the circuit in the movement of the vehicle, and means for determining the further state of operation thereof including cooperating vehicle and 115 roadside inductive elements connected for operation to said source of energy.

7. In an alternating current inductive train control system, vehicle carried mechanism, means including roadside mechanism for influencing the same in the movement of the vehicle to produce a predetermined effect therein, means operable when the same is so influenced for modifying the effect under given track conditions to produce a different effect therein, the latter means comprising cooperative vehicle and roadside inductive elements, and a vehicle alternating current source of energy for operating said elements. 120 125

8. In an alternating current inductive train control system, vehicle carried mechanism, means including roadside mechanism for influencing the same in the movement of the vehicle to produce a "danger" effect therein, 5 means operable when the same is so influenced for differently modifying the effect under "safe" and "caution" track conditions to produce proceed and speed restrictive effects therein, the latter means comprising co-operative vehicle and roadside inductive elements, and a vehicle alternating current source of energy for operating said elements. 10
9. In an alternating current induction train control system, vehicle carried mechanism, means including roadside mechanism for influencing the same in the movement of the vehicle to produce a "danger" effect therein, 15 means operable substantially when the same is so influenced for modifying the effect under "safe" and "caution" track conditions to produce "safe" and "caution" effects, the latter means comprising vehicle transmitting and receiving inductoriums, track receiving and transmitting inductoriums cooperating therewith, a vehicle alternating current source of energy for generating impulses in said track receiving inductorium for transmission to the track transmitting inductorium in the movement of the vehicle, and roadside means operable 20 in response to track conditions for governing the characteristic of the impulse transmitted 25 to the track transmitting inductorium. 30
10. In an alternating current train control system, vehicle carried mechanism including a train controlling means and a speed controller, means including roadside mechanism 40 for influencing the train controlling means in the movement of the vehicle, means for determining the operation of the same when so influenced including cooperating vehicle and roadside inductive elements operable in 45 response to track conditions, a vehicle alternating current source of energy for operating the inductive elements, and provisions for placing the train controlling means under the control of the speed controller when 50 the inductive elements cooperate under "cautionary" track conditions. 55
11. In an alternating current inductive train control system, vehicle carried mechanism and provisions for controlling the same, 60 said provisions including an impulse transmitting roadside inductorium, an impulse receiving vehicle inductorium, means including a vehicle alternating current source of energy for producing an impulse in said roadside inductorium, and roadside means for governing the direction of flow of said impulse to said roadside inductorium. 65
12. In an alternating current inductive train control system, vehicle carried mechanism and provisions for controlling the same, 70 said provisions including an impulse transmitting roadside inductorium, and impulse receiving vehicle inductorium, means including an alternating current source of energy for producing an impulse for transmission to said roadside inductorium, and roadside means operative for effecting, modifying and inhibiting the transmission of such impulse to selectively produce any of three different conditions in said inductorium. 75
13. In an alternating current inductive train control system, vehicle carried mechanism and provisions for controlling the same, 80 said provisions including an impulse transmitting roadside inductorium, an impulse receiving vehicle inductorium, means including a vehicle alternating current source of energy for producing an impulse for transmission to said roadside inductorium, and roadside means operative for effecting, modifying and inhibiting the transmission of such impulse, said roadside means including a pole changer and a make and break device. 85
14. In an alternating current induction train control system, vehicle carried mechanism and provisions for controlling the same, 90 the said provisions including roadside receiving and transmitting inductoriums, vehicle transmitting and receiving inductoriums, a vehicle alternating current source 95 of energy therefor, and means for connecting the roadside inductoriums operative to reverse circuit connections therebetween. 100
15. In an alternating current induction train control system, vehicle carried mechanism and provisions for controlling the same, 105 the said provisions including roadside receiving and transmitting inductoriums, vehicle transmitting and receiving inductoriums, a vehicle alternating current source of energy therefor, and means for connecting the roadside inductoriums operative to reverse circuit connections and for breaking circuit connections therebetween. 110
16. In an alternating current inductive train control system, vehicle carried means and provisions for controlling the same to produce "safe," "caution" and "danger" effects therein including a roadside inductorium system, a vehicle inductorium system 115 cooperating therewith, a vehicle alternating current source of energy for energizing the inductorium systems, and roadside mechanism for controlling the same to respond to "safe," "caution" and "danger" track conditions. 120
17. In an alternating current inductive train control system, vehicle carried means and provisions for controlling the same to produce "safe," "caution" and "danger" effects therein including a roadside inductorium system, a vehicle inductorium system 125 cooperating therewith, a vehicle alternating current source of energy for energizing the inductorium systems, and roadside mecha- 130

nism for controlling the same to respond to "safe," "caution" and "danger" track conditions, said roadside mechanism including a circuit changer and a make and break device.

5 18. In an alternating current train inductive control system, vehicle carried means operative to produce a predetermined effect, roadside means for producing such effect, and means for modifying such effect including a vehicle inductive impulse receiver, a roadside inductive impulse transmitter independent of said roadside means with which said receiver is cooperable substantially when such effect is produced, and an alternating current source of electrical energy on the vehicle for energizing the inductive transmitter and receiver.

20 19. In an alternating current inductive train control system, vehicle carried mechanism, means including roadside mechanism for influencing the same in the movement of the vehicle to produce a given effect therein under a given track condition, means operable substantially when the same is so influenced for producing either of two other effects therein under either of two other track conditions, the latter means comprising cooperative vehicle and roadside magnetic elements and a vehicle alternating current source of energy for operating the same.

25 20. In an alternating current induction train control system, vehicle carried mechanism, means including roadside mechanism for influencing the same in the movement of the vehicle to produce a given effect therein under a given track condition, and means operable substantially when the same is so influenced for producing either of two other effects therein under either of two other conditions, the latter means comprising vehicle transmitting and receiving inductoriums, track receiving and transmitting inductoriums cooperating therewith, a vehicle alternating current source of energy for generating an impulse in said track receiving inductorium for transmission to the track transmitting inductorium in the movement of the vehicle, and roadside means operable in response to track conditions for governing the characteristic of the impulse transmitted to the track transmitting inductorium.

30 21. In a train control system, in combination, vehicle mechanism comprising a transformer including primary and secondary coils having a magnetic path containing reluctance and roadside mechanism comprising a magnetic shunt operative when the vehicle mechanism moves in proximity thereto for shunting the magnetic flux from the secondary of the transformer.

35 22. In a train control system, in combination, vehicle mechanism comprising induct-

tively coupled coils and roadside mechanism comprising a magnetic member operative when the vehicle mechanism moves in proximity thereto for magnetically shunting one of said coils.

70 23. In a train control system, in combination, vehicle mechanism comprising a pair of inductively coupled coils, vehicle control means influenced by one of said coils, a source of energy connected to the other of said coils, and roadside mechanism comprising a magnetic member operative when the vehicle mechanism moves in proximity thereto for magnetically shunting one of said coils, for operating said vehicle control means.

75 24. In a train control system, in combination, vehicle mechanism comprising inductively coupled coils and roadside mechanism comprising a magnetic member operative when the coupled coils move in proximity thereto for magnetically shunting one of said coils.

80 25. In an inductive train control system, vehicle carried train control mechanism, means for influencing the same in the movement of the vehicle upon a roadway comprising a vehicle carried transformer including primary and secondary coils, and a roadside element for shunting the secondary coil when the transformer is brought into magnetic relation therewith, and means for determining the further state of operation of the mechanism when so influenced.

85 26. In a train control system, vehicle carried mechanism, means for influencing the same in the movement of the vehicle over a roadway comprising a vehicle carried transformer including primary and secondary coils having reluctance in the magnetic path between the same and a roadside element for shunting the secondary coil when the transformer is brought into magnetic relation therewith, and means for determining the further state of operation of the mechanism when so influenced including cooperating vehicle and roadside magnetic elements.

90 27. In a train control system, vehicle carried mechanism, means for influencing the same in the movement of the vehicle to produce a controlling effect therein, said means comprising a vehicle carried transformer including primary and secondary coils, and a roadside element for shunting the secondary coil when the transformer is brought into magnetic relation therewith, and means for determining the further state of operation of the mechanism when the same is controlled.

95 28. In a train control system, vehicle carried mechanism, means for influencing the same in the movement of the vehicle to produce a controlling effect therin, said means comprising a vehicle carried transformer including primary and secondary coils having reluctance in the magnetic path between

- the same and a roadside element for shunting the secondary coil when the transformer is brought into magnetic relation therewith, and means for determining the further state of 5 operation of the mechanism when the same is controlled including cooperative vehicle and roadside magnetic elements and a vehicle source of energy for operating the said magnetic elements.
- 10 29. In an inductive train control system, vehicle carried mechanism including a normally closed operating circuit, means for influencing the same in the movement of the vehicle upon a roadway comprising a vehicle 15 carried transformer including primary and secondary coils having reluctance in the magnetic path between the same and a roadside element for shunting the secondary coil when the transformer is brought into magnetic relation therewith, and means for determining the further state of operation of said circuit including cooperating vehicle and roadside magnetic elements.
- 20 30. In an inductive train control system, vehicle carried mechanism, means for influencing the same in the movement of the vehicle to produce a predetermined effect therein, said means comprising a vehicle carried transformer including primary and secondary coils having reluctance in the magnetic path between the same and a roadside element for shunting the secondary coil when the transformer is brought into magnetic relation therewith, and means operable when 25 the mechanism is so influenced for modifying the effect under given track conditions to produce a different effect therein, the latter means comprising cooperative vehicle and roadside magnetic elements.
- 30 31. In a train control system, vehicle carried mechanism including a train controlling means and a speed controller, means for influencing the train controlling means in the movement of the vehicle comprising a vehicle 35 carried transformer including primary and secondary coils having reluctance in the magnetic path between the same and a roadside element for shunting the secondary coil when the transformer is brought into magnetic relation therewith, and means for determining the operation of the train controlling means when so influenced including cooperating vehicle and roadside magnetic elements operable in response to track conditions, and 40 provisions for placing the train controlling means under the control of the speed controller when the magnetic elements cooperate under predetermined track conditions.
- 45 32. In an inductive train control system, vehicle carried mechanism, means for influencing the same in the movement of the vehicle to produce a given effect therein under a given track condition, said means comprising a vehicle transformer having primary and 50 secondary coils provided with a magnetic 55 path having reluctance between the coils and a roadside element for shunting the secondary coil when the transformer is brought into magnetic relation therewith, means operable when the mechanism is so influenced for producing either of two other effects therein under either of two other track conditions, the latter means comprising cooperative vehicle and roadside magnetic elements and a vehicle source of energy for operating the same.
- 60 33. In an inductive train control system, vehicle carried train control mechanism, means for periodically influencing the same in the movement of a vehicle on a roadway including vehicle carried inductively coupled coils and a roadside element for magnetically shunting one of said coils when the latter are brought into magnetic relation therewith, and means for periodically determining the further state of operation of the said mechanism when so influenced comprising vehicle impulse transmitting and receiving inducto- 65 riums, a source of energy therefor, and track impulse receiving and transmitting inducto- 70 riums cooperating therewith.
- 75 34. In a train control system, vehicle carried mechanism, means for influencing the same in the movement of the vehicle over a roadway including vehicle carried inductively coupled coils and a roadside element for magnetically shunting one of said coils when the latter are brought into magnetic relation therewith, and means for determining the operation of the mechanism when so influenced including cooperative vehicle and roadside magnetic elements and a vehicle source of energy for energizing the vehicle magnetic element by way of the roadside magnetic element.
- 80 35. In an alternating current train control system, vehicle carried mechanism, means for influencing the same in the movement of the vehicle over a roadway including vehicle carried inductively coupled coils and a roadside element for magnetically shunting one of said coils when the latter are brought into magnetic relation therewith, and means for determining the operation of the mechanism when so influenced including cooperative vehicle and roadside magnetic elements and a vehicle 85 source of energy for energizing the vehicle magnetic element by way of the roadside magnetic element.
- 90 36. In a train control system, vehicle carried mechanism, means for influencing the same in the movement of the vehicle to produce a controlling effect therein, said means including vehicle carried inductively coupled coils and a roadside element for magnetically shunting one of said coils when the latter are 95 brought into magnetic relation therewith, and means for determining the state of operation of said mechanism when the same is controlled.
- 100 37. In a train control system, vehicle car- 105

ried mechanism, means for influencing the same in the movement of the vehicle to produce a controlling effect therein, said means including vehicle carried inductively coupled 5 coils and a roadside element for magnetically shunting one of said coils when the latter are brought into magnetic relation therewith, and means for determining the state of operation of said mechanism when the same is 10 controlled including cooperative vehicle and roadside magnetic elements, and a vehicle source of energy for operating said magnetic elements.

38. In an inductive train control system, 15 vehicle carried mechanism, means for influencing the same in the movement of the vehicle to produce a predetermined effect therein, said means including vehicle carried inductively coupled coils and a roadside element for magnetically shunting one of said coils 20 when the latter are brought into magnetic relation therewith, means operable when the mechanism is so influenced for modifying the effect under given track conditions to 25 produce a different effect therein, the latter means comprising cooperative vehicle and roadside magnetic elements and a vehicle source of energy for operating the same.

39. In a train control system, vehicle carried mechanism including a train controlling 30 means, a speed controller, means for influencing the train controlling means in the movement of the vehicle including vehicle carried inductively coupled coils and a roadside element for magnetically shunting one 35 of said coils when the latter are brought into magnetic relation therewith, means for determining the operation of the said train controlling means when so influenced including cooperating vehicle and roadside magnetic elements operable in response to track 40 conditions and provisions for placing the train controlling means under the control of the speed controller when the magnetic elements 45 cooperate under predetermined track conditions.

40. In a train control system the combination of apparatus on the moving vehicle comprising a relay, a transformer which energizes the relay, means for stopping the train 50 controlled by said relay, a source of energy, two inductoriums one acting as a transmitter and the other as a receiver, a reset relay in circuit with said receiver inductorium and 55 designed to be influenced thereby, and means for restoring said train stopping means by said reset relay that the train may continue, and apparatus on the track comprising an inert magnetic element, a receiver inductorium, a transmitter inductorium, a circuit 60 connecting said track inductoriums and means in said circuit whereby it may be opened or the relative instantaneous polarity between the two track inductoriums may be 65 changed.

41. In a device for stopping a railway train and for other purposes, the combination of a source of energy, a transformer energized thereby, a device energized by said transformer, means for controlling the train 70 and a magnetic element in the track, so arranged that when the transformer comes into correspondence with the magnetic element, the flux in the field of said transformer is shunted from the secondary of the transformer, thus causing said device to become 75 operative to influence the train controlling means.

42. A transformer having a primary and a secondary winding, with an air gap for reluctance between the magnetic cores of said windings, all so arranged that when said transformer is brought into proximity with a magnetic element flux in said transformer core is diverted through said magnetic element and shunted from said secondary core. 80

43. A transformer having primary and secondary coils, with an air gap for magnetic reluctance in the magnetic path connecting said coils, such that when the said transformer is brought into proximity with a magnetic element, flux in the magnetic path through said primary and secondary coils is diverted through the magnetic element, 85 shunting said secondary coil such that the current in its circuit is so reduced that any relay in its circuit will be influenced thereby. 90

44. In a device for stopping a railway train, the combination of a source of energy, a transformer energized thereby, a relay energized from the secondary of said transformer, a plurality of circuits under the control of the relay, and an electro-magnet air valve, in one circuit, all carried on the train, and a magnetic element located on the roadside, the arrangement being such that when there is correspondence between the transformer and the magnetic element the flux through the secondary coil of the transformer is shunted so that the current in its circuit is greatly reduced, thus causing the circuit to operate and in turn operate the electro-magnet air valve to apply the air brakes and stop the train. 100

45. A combination for translating a condition through an air gap comprising a transformer having a primary and a secondary coil with a magnetic path containing reluctance between the two, a relay in circuit with said secondary coil and responsive to fluctuation of current therein, and a magnetic element always separated from said transformer by an air gap, all so arranged that when there is correspondence between said transformer and said magnetic element, the latter influences the former to shunt magnetic flux from the secondary and cause the relay to operate. 115

46. In combination, vehicle carried means to be operated according to track conditions 130

- including a circuit having a source of fluctuating current and a reactance coil adapted to move past track armatures to change the characteristics of the circuit to operate said means, 5 an inductive impulse receiver carried by the vehicle and controlling said means to modify the operation thereof, an inductive impulse transmitter connected in circuit with said source of fluctuating current and carried by 10 the vehicle, and controlled means on the track for transferring the inductive impulses from said transmitter to the receiver.
47. In a train control system of the type in which the car-carried train control apparatus if initiated continues to be effective until restored, a trackway device for initiating the operation of said apparatus constituting an inert mass of iron when in its active condition, and other trackway means for restoring 15 20 said device comprising two inert masses of iron having windings connected in series in a circuit of low resistance when in their active condition.
48. In a train control system of the type in which a brake control mechanism is employed, which if initiated will continue to be effective until restored, trackway means acting through an air gap for initiating said mechanism; and means for restoring said mechanism comprising, a track element which is energized by a source of energy on the train when the train passes thereby, and car-carried means adapted to be inductively influenced by said energized track element.
49. In a train control system, the combination with brake control apparatus on a vehicle of the type which continues effective when set into operation until restored, of traffic controlled means for restoring said apparatus comprising, a source of electrical energy on the vehicle, and means on the trackway energized from said source and governed by electrical circuits which must be closed to permit the restoration of said apparatus.
50. In combination, vehicle carried means to be operated according to track conditions including a circuit having a source of fluctuating current and a device adapted to move past track armatures to affect the circuit to 50 operate said means, an inductive impulse receiver carried by the vehicle and controlling said means to modify the operation thereof, an inductive impulse transmitter connected in circuit with said source of fluctuating current and carried by the vehicle, and controlled means on the track for transferring the inductive impulses from said transmitter to the receiver.
51. In an automatic train control system, 60 the combination of means for transmitting danger control influences comprising, car-carried devices and circuits in which each circuit is energized by alternating current, said devices being adapted to be actuated by trackway devices constituting an inert magnetic

body when in their active condition; and means for transmitting restoring influences comprising, a car-carried influence transmitting means and a car-carried influence receiving means; and a trackway device comprising, two track elements having their coils connected in a circuit when in their active restoring condition.

52. In an automatic train control system, an organization for communicating distinctive initiating and restoring influences from the trackway to a moving car inductively through an intervening air gap comprising, a source of alternating current on the car, car-carried devices and circuits all normally energized from said source and including a control relay adapted whenever deenergized to remain in that condition until specially restored, a track device constituting an inert magnetic body in its active stopping condition and if in that condition influencing said car-carried devices and circuits to cause deenergization of said control relay, a normally deenergized relay on the car adapted when energized to restore said control relay to its normal energized condition, and means including a traffic controlled circuit on the trackway for transmitting energy from said source on the car to said normally deenergized relay provided said circuit on the trackway is closed.

53. In a train control system, the combination with a track device constituting an inert magnetic body in the active stopping condition, car apparatus cooperating with the track device and comprising, a two-element alternating current relay, a source of alternating current, and inductively associated coils arranged to pass over said track device and have the reluctance of their magnetic circuits changed by the magnetic qualities of said track device, one of said coils being connected to said source and the other to one field element of the relay.

54. A system for communicating distinctive initiating and restoring influences from a trackway to a moving car thereon inductively through an intervening air gap comprising, an inert non-magnetized magnetic core on the trackway, a car-carried device cooperating with said core, a source of alternating current on the car, electro-responsive means normally energized from said source and deenergized by the cooperation of said car-carried device with the trackway core, said electro-responsive means whenever deenergized remaining in that condition until specially restored, and means energized wholly from said car-carried source of current and including a circuit on the trackway for restoring said electro-responsive means to normal only if said circuit on the trackway is closed.

55. Car equipment for train control systems comprising, a source of alternating current, a normally deenergized and a normally

energized two-element alternating current relay, each of said relays having one field element connected to said source, and automatic means adapted to be influenced from the trackway for independently supplying current from said source to the other field elements of said relays.

56. An automatic train control system comprising, a normally energized control relay 10 on a vehicle having its energizing circuit completed through its own front contacts inductive communicating means partly on the vehicle and partly on the track for momentarily deenergizing said relay, and means on 15 the vehicle actuated through an intervening air gap from the trackway and deriving its energy from a vehicle carried source for momentarily shunting said front contact.

57. In a train control system, the combination 20 with car equipment comprising a control stick relay, brake control apparatus effective and ineffective as the relay is de-energized and energized respectively, a pick-up circuit for the relay, receiving means adapted to be influenced by a trackway field 25 of flux for energizing the pick-up circuit, and a source of magneto-motive force, of traffic controlled trackway devices excited from the source of magneto-motive force on the vehicle 30 for producing a field of flux to effect said receiving means under clear traffic conditions.

58. In a train control system, the combination 35 with brake control apparatus on a vehicle requiring restoration after each operation, a normally deenergized circuit on the vehicle adapted when energized to restore said apparatus, and track circuit controlled means partly on the vehicle and partly on 40 the track deriving its energy wholly from a source on a vehicle for causing energization of said circuit, said means acting inductively through an air gap.

59. An intermittent inductive train control 45 system comprising, in combination, vehicle carried mechanism including inductively coupled elements normally coupled together for direct energy transference therebetween, an alternating current source connected to one of the coupled elements and a controlled circuit connected to another of the coupled elements, and roadside mechanism including a magnetic member cooperating inductively with the vehicle carried inductively 55 coupled elements when said elements move over and in proximity to said magnetic member in the movement of the vehicle over the roadside for decreasing the direct energy transference between said inductively coupled elements.

60. An intermittent inductive train control 60 system comprising, in combination, vehicle carried mechanism including inductively coupled coils normally coupled together for 65 direct energy transference therebetween, and

roadside mechanism including an inductor cooperating inductively with the vehicle carried coupled coils when said coils move over and in proximity to said roadside inductor in the movement of the vehicle over the roadside for decreasing the direct energy transference between said coupled coils.

61. An inductive train control system comprising, in combination, vehicle carried mechanism including inductively coupled coils 70 normally coupled together for energy transference therebetween, a train control device normally energized by said coils, and roadside mechanism for effecting the deenergization and restoration of said train control device comprising an inductor cooperating inductively with the vehicle carried coupled coils when said coils move over and in proximity to said inductor in the movement of the vehicle over the roadside for decreasing the effective energy transference between said inductively coupled elements to deenergize 80 said device, and inductive means controlled from the roadside for restoring the operation of said train control device.

62. An intermittent inductive train control system comprising, in combination, vehicle carried mechanism including inductively coupled elements normally coupled together for energy transference therebetween, an alternating current source connected to one of the coupled elements and a controlled circuit connected to another of the coupled elements, and roadside mechanism including spaced magnetic members cooperating intermittently with the vehicle carried mechanism in the movement of the vehicle over the roadside, each roadside magnetic member cooperating inductively with the vehicle carried inductively coupled elements when said elements move over and in proximity to said magnetic member for decreasing the effective energy transference between said inductively coupled elements.

63. An intermittent inductive train control 100 system comprising, in combination, vehicle carried mechanism including inductively coupled coils normally coupled together for direct energy transference therebetween and having reluctance in the inductive path therebetween, and roadside mechanism including spaced inductors cooperating intermittently with the vehicle carried mechanism in the movement of the vehicle over the roadside, each roadside inductor cooperating inductively with the vehicle carried inductively coupled coils when said coils move over and in proximity to said roadside inductor for decreasing the direct energy transference between said inductively coupled coils.

64. An intermittent inductive train control 115 system comprising, in combination, vehicle carried mechanism including a source of energy, a train controlling device, an energy transmitting coil connected to said source of 120

- energy, an energy receiving coil normally inductively coupled to said energy transmitting coil for receiving energy therefrom and connected to said train controlling device, and roadside mechanism including a magnetic member cooperating inductively with the vehicle carried energy transmitting and receiving coils when said coils move over and in proximity to said magnetic member for decreasing the direct energy transference between said vehicle inductively coupled coils.
65. An inductive train control system comprising, in combination, vehicle carried mechanism including a source of energy, a train controlling device, an energy transmitting coil connected to said source of energy, an energy receiving coil normally inductively coupled to said energy transmitting coil for receiving energy therefrom and connected to said train controlling device for normally energizing the same, the said coils being coupled with reluctance in the inductive path therebetween, and roadside mechanism including an inductor cooperating inductively with the vehicle carried energy transmitting and receiving coils when said coils move over and in proximity to said inductor for affecting the direct energy transference between said vehicle inductively coupled coils to effectively deenergize and trip said train controlling device.
66. An intermittent inductive train control system comprising, in combination, vehicle carried mechanism including a source of energy, a train controlling device, an energy transmitting coil connected to said source of energy, an energy receiving coil normally inductively coupled to said energy transmitting coil for directly receiving energy therefrom and connected directly in circuit to said train controlling device, and roadside mechanism including an inductor cooperating inductively with the vehicle carried energy transmitting and receiving coils when said coils move over and in proximity to said inductor for affecting the energy transference between said vehicle inductively coupled coils to effectively deenergize and trip said train controlling device.
67. An intermittent inductive train control system comprising, in combination, vehicle carried mechanism including an alternating current source of energy, a train controlling device, an energy transmitting coil connected in circuit to said source of energy, an energy receiving coil normally inductively coupled to said energy transmitting coil for receiving energy therefrom and connected directly in circuit to said train controlling device for normally energizing said device, and roadside mechanism including spaced magnetic members cooperating intermittently with the vehicle carried mechanism in the movement of the vehicle over the roadside, a roadside magnetic member cooperating inductively

with the vehicle carried coupled coils when said coils move over said magnetic member for changing the energy transference between said inductively coupled coils to effectively deenergize said train controlling device.

68. An intermittent inductive train control system comprising, in combination, vehicle carried mechanism including an alternating current source of energy, a train controlling device, an energy transmitting coil connected in circuit to said source of energy, an energy receiving coil normally inductively coupled to said energy transmitting coil for directly receiving energy therefrom and connected directly in circuit to said train controlling device for normally energizing said device, and roadside mechanism including spaced inductors cooperating intermittently with the vehicle carried mechanism in the movement of the vehicle over the roadside, each roadside inductor cooperating inductively with the vehicle carried coupled coils when said coils move over and in proximity to said roadside inductor for changing the energy transference between said inductively coupled coils to effectively decrease the current in the circuit to said train controlling device.

69. An intermittent inductive train control system comprising, in combination, vehicle carried mechanism including an alternating current source of energy, a train controlling device, an energy transmitting coil connected in circuit to said source of energy, an energy receiving coil normally inductively coupled to said energy transmitting coil for receiving energy therefrom and connected directly in circuit to said train controlling device for normally energizing said device, and roadside mechanism including an inductor cooperating inductively with the vehicle carried coupled coils when said coils move over said inductor for changing the energy transference between said inductively coupled coils to effectively deenergize said train controlling device and trip said vehicle carried mechanism, said vehicle carried and roadside mechanism including vehicle carried and roadside inductors operated from a vehicle carried source of energy and effective for restoring the vehicle carried mechanism.

70. An intermittent inductive train control system comprising, in combination, vehicle carried mechanism including an alternating current source of energy, a train controlling device, an energy transmitting coil connected in circuit to said source of energy, an energy receiving coil normally inductively coupled to said energy transmitting coil for receiving energy therefrom and connected directly in circuit to said train controlling device for normally energizing said device, and roadside mechanism including an inductor cooperating inductively with the vehicle carried coupled coils when said coils move over said inductor for changing the energy transference between said inductively coupled coils to effectively deenergize said train controlling device.

- ence between said inductively coupled coils to effectively deenergize said train controlling device and trip said vehicle carried mechanism, said vehicle carried and roadside mechanism including a vehicle carried inductor and a roadside inductor operated from said vehicle carried source of energy and effective for restoring the vehicle carried mechanism.
- 10 71. An intermittent inductive train control system comprising, in combination, vehicle carried mechanism including a source of energy, a train controlling device, an energy transmitting coil connected to said source of energy, an energy receiving coil normally inductively coupled to said energy transmitting coil for receiving energy therefrom and connected to said train controlling device for normally energizing said device, and roadside mechanism including an inductor cooperating inductively with the vehicle carried energy transmitting and receiving coils when said coils move over and in proximity to said inductor for decreasing the direct energy transference between said vehicle inductively coupled coils and thereby tripping said vehicle carried mechanism, said vehicle carried and roadside mechanism including vehicle carried and roadside inductors operative for restoring the vehicle carried mechanism, and a vehicle carried source of energy for operating the said inductors.
- 15 72. An intermittent inductive train control system comprising, in combination, vehicle carried mechanism including a source of energy, a train controlling device, an energy transmitting coil connected to said source of energy, an energy receiving coil normally inductively coupled to said energy transmitting coil for receiving energy therefrom and connected to said train controlling device for normally energizing said device, and roadside mechanism including an inductor cooperating inductively with the vehicle carried energy transmitting and receiving coils when said coils move over and in proximity to said inductor for decreasing the direct energy transference between said vehicle inductively coupled coils and thereby tripping said vehicle carried mechanism, and means energized wholly from said vehicle carried source of energy and including a circuit on the roadside for restoring said vehicle carried mechanism only if said circuit on the roadside is closed.
- 20 73. An intermittent inductive train control system comprising, in combination, vehicle carried mechanism including an alternating current source of energy, a train controlling device, an energy transmitting coil connected in circuit to said source of energy, an energy receiving coil normally inductively coupled to said energy transmitting coil for receiving energy therefrom and connected directly in circuit to said train controlling device for normally energizing said device, and roadside mechanism including an inductor cooperating inductively with the vehicle carried energy transmitting and receiving coils when said coils move over and in proximity to said inductor for changing the energy transference between said inductively coupled coils to effectively deenergize said train controlling device and trip said vehicle carried mechanism, and means energized wholly from said vehicle carried source of energy and including a circuit on the roadside for restoring said vehicle carried mechanism only if said circuit on the roadside is closed.
